UNITED STATES PATENT OFFICE.

JAY M. AXTELL AND FREDERICK G. VON HOFEN, OF FORT WORTH, TEXAS, ASSIGNORS
TO A.V. BURNER COMPANY, OF FORT WORTH, TEXAS, A CORPORATION OF TEXAS.

CIRCULATING GAS BURNER.

Application filed November 21, 1925. Serial No. 70,475.

Our invention relates to gas burners and more particularly to circulating gas burners; and the object is to provide pipes for supplying the gas to the burners which are 5 adapted to cause a circulation of the gas throughout the lengths of the burner pipes so that the pressure will be uniform throughout the length of the burner pipes. The advantage of this provision is that the jets 10 of flame will be uniform and not weak at points remote from the entrance of the gas into the burner pipes. Our present invention is an improvement on the patents granted to us on September 1, 1925, for gas burners, Nos. 1,551,532 and 1,552,190. Other objects and advantages will be fully explained in the following description and the invention will be more particularly pointed out in the claims.

Reference is had to the accompanying drawings which form a part of this application.

Fig. 1 is a longitudinal section of the burner pipes.

Fig. 2 is a cross-section of the pipes and a vertical section of a pair of burner tips.

Fig. 3 is a similar view to the view of Fig. 2, showing a variation in the form of burner tips.

Similar characters of reference are used to indicate the same parts throughout the several views.

The drawing shows a supply pipe 1 provided with a cock or valve 2. The burner 35 is provided with a casting 3 which is screwed on the pipe 1. The burner is provided with an inner circulating member 4 and an outer circulating member 5. The casting 3 has a series of graduated cavities in which the 40 burner pipes are screwed. A feed pipe 6 is screwed into the smallest cavity and the inner circular member 4 has the end thereof screwed into the next larger cavity and the outer circular member 5 has the end 45 screwed into the largest cavity in the casting 3 which serves as a holder or support for the circulating members. The outer circulating member 5 is provided with a cap 7. The member 5 is to be tapped at suitable 50 places into the outer circulating member 5 for burner tips 8 of the ordinary type or for tips 9. It is apparent that tips of the forms 8 and 9 can be varied and that the tips may be dispensed with and orifices drilled in the 55 pipes at the required angle for distribution

in order to secure proper combustion. The tips or nozzles may be distributed throughout the length of the outer circulating member 5. Gas is to be delivered to the inner circulating member 4 by the feed nozzle 6. 60 Gas escapes from the end of the member 4 and will be directed back into the outer member 5 to be fed to the various burner tips. The gas which is not consumed through the burner tips will be directed back into member 4 through the perforations 10 and the nozzle 6 will cause a suction because the pressure through the nozzle will be greater than the pressure coming from the perforations 10 and the gas from the perforations 10 will be 70 caught up and forced along with the fresh supply coming through the nozzle 6. In this manner there will be maintained a pressure or head of gas throughout the pipe 4 and the pipe 5 so that the pressure will be uniform and the pressure will be uniform through the orifices of all the tips or nozzles. The gas is thus stored in the pipe 5 with sufficient head or pressure to make the feeding of gas through the tips or nozzles 80 uniform.

What we claim, is,—

1. A circulating burner comprising a holder, an outer circulating member rigid with said holder and provided with burner 85 nozzles, a circulating member within said outer member rigid with said holder and open at the opposite end for permitting gas to enter said outer member and having perforations near said holder for permitting 90 gas to enter therein from said outer member, and a feed nipple rigid with said holder for supplying gas to said inner member and projecting beyond said perforations for aiding in directing gas from the outer to the 95 inner member.

2. A circulating gas burner comprising a holder, an outer circulating member rigid with said holder and provided with burner nozzles, a circulating member within said 100 outer member rigid with said holder and open at the opposite end for permitting gas to enter said outer member and having perforations near said holder for permitting gas to enter thereinto from said outer member, said outer and inner members serving to maintain a head of gas and tending to equalize the pressure throughout both members, and a feed nipple connected with a supply source of gas and projected beyond 105 110

said perforations and tending to create suction for drawing gas through said perforations.

3. A circulating burner comprising a burner tube provided with burner nozzles and an inner circulating and distributing pipe located within said tube and spaced therefrom and open at one end for supplying gas to said tube, a feed nipple for supplying gas to said circulating and distributing pipe projecting within said pipe, and means for sealing said burner tube about the receiving end of said pipe and holding the same in spaced relation to said pipe and

for sealing said pipe about said feed nipple and holding the same in spaced relation to said nipple, said pipe having intake openings near the receiving end to receive unconsumed gas from said tube and said feed nipple projecting past said intake openings for utilizing the draft through the feed nipple to draw gas through said intake openings into said circulating and distributing pipe.

In testimony whereof, we set our hands, 25
this 31st day of October, 1925.

JAY M. AXTELL.

FREDERICK G. VON HOFEN.
